Primary Examiner — Andrew T Nemeth(74) Attorney, Agent, or Firm — Shen Huang(57) CLAIM

The ornamental design for an elizabethan pet collar, as shown and described.

DESCRIPTION

FIG. 1 is a perspective view of an elizabethan pet collar, shown closed in a first configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top elevation view of the elizabethan pet collar of FIG. 1, shown open and flattened in a second configuration.

The broken lines illustrate portions of the elizabethan pet collar that form no part of the claimed design.
